UNITED STATES PATENT OFFICE

JOHN D. OTTO, OF GALVA, IOWA

PULLING DEVICE

Application filed May 14, 1928. Serial No. 277,576.

My invention comprises a puller, which can be used for pulling a variety of articles, but is particularly adapted for pulling metal fence posts from the ground.

5 A particular object of my invention is to provide such a puller having a standard and article engaging means arranged to travel in a path spaced laterally from the standard, which path is free from any other projecting parts of the puller, and to provide means mounted on the standard for operating the article engaging means in such manner that the article to be pulled, such as a post, may be gripped, and the article engag- 10 ing means may then be pulled with tremendous power for moving the post or the like for a short distance, and then the article engaging means can be slid along the post to a new engaging or gripping position.

15 Another important object of the present invention is to provide such an article engaging means, which includes a pair of jaws pivotally mounted on a plate or equivalent support, and having projecting ends to which 20 are pivoted the lower ends of arms, which arms are in turn pivoted at their upper ends to a lever fulcrumed on the standard.

Another object is to provide a structure of the kind just mentioned in which the 25 weight of the plate tends to move the post to article engaging position.

Still another object is to provide such a structure in which the arms are pivoted to the lever to permit the swinging of the plate 30 and the jaws mounted thereon toward and from the standard.

An additional object is to provide in such a puller means tending to yieldingly swing the article engaging device away from the 35 standard, so that when the standard is placed in proper position with relation to a post and parallel therewith, the last-mentioned means will tend to yieldingly press the article engaging means against the post, whereby 40 by the article engaging means can be slid up and down the post for pulling the post a certain distance during the operative stroke of the lever, and for sliding the article engaging means to another position during the 45 return stroke of the lever, and whereby dur-

ing such return stroke, the grip of the article engaging means on the post will be automatically released.

This application is in part a continuation 55 of my application, Serial No. 256,012, filed February 21, 1928.

With these and other objects in view, my invention consists in the construction, arrangement and combination of the various parts of my pulling device, whereby the objects contemplated are attained, as herein- 60 after more fully set forth, pointed out in my claims, and illustrated in the accompanying drawings, in which:

Figure 1 shows a side elevation of my im- 65 proved pulling device arranged in operative position with relation to a post to be pulled.

Figure 2 is a detail, sectional view taken on the line 2—2 of Figure 1.

Figure 3 is a view similar to that of Figure 2 with the post engaging jaws in inop- 70 erative position.

Figure 4 is a detail, sectional view taken on the line 4—4 of Figure 1; and

Figure 5 is a perspective view of the plate 75 on which the jaws are pivoted, illustrating particularly the back side of the plate.

In the drawings herewith, I have illus- 80 trated a form in which my invention may be embodied.

I provide a standard comprising the up- 85 right member indicated by the reference numeral 10. The standard 10 has a suitable base 12, which is provided on what may be called the front side of the pulling device with a recess 14, so that the base may be set in position where the post 16 to be pulled is received in the recess 14.

While the standard 10 is illustrated as being 90 made of a piece of tubular pipe, it may be understood that it may be made of angle bar or bars or of any material, and in any form suitable for the purpose.

The base 12 is preferably beveled as indi- 95 cated at 18 to permit it to be conveniently slid under woven wire fencing or the like.

Pivoted to the upper end of the standard 10 is a lever 20. Pivoted to the short end of the lever 20 are down hanging arms 22,

which diverge at their lower ends as shown in Figure 2.

The pivot pin 24 at the upper ends of the arms 22 is so arranged that the arms 22 swing toward and from the standard 10.

I provide in my pulling device an article gripping or engaging means. The article engaging means includes a plate 26, in the front face of which is a vertical groove 28 adapted to receive the vertical flange 16^a of the post 16 already mentioned.

Pivottally mounted on the front face of the plate 26 are members 30 having at their inner ends the coacting corrugated jaws 32. These jaws 32 are slightly curved as illustrated in Figures 2 and 3.

The lower ends of the arms 22 are pivoted to the outer ends of the members 30. The parts are shaped and constructed so that when the lever 20 is manipulated for reciprocating the plate 26, that plate can slide or reciprocate in a plane parallel with the vertical axis of the standard 10.

This result may be accomplished by bending the arms 22 slightly as indicated at 22^a in Figure 1.

Supported on the standard 10 is a spring A, preferably having a coil portion 34 adjacent to the standard 10 and a slightly curved portion 36 extending away therefrom. The portion 36 of the spring A is extended slidably through a suitable guide or guides 38 on the plate 26. The portion 36 stands in a vertical plane when the standard 10 is upright, and the guide means 38 are so arranged as to hold the plate 26 against lateral swinging movement.

This arrangement and construction of parts serves to accomplish the purpose of holding the plate 26 in such position that the members 30 tend to be normally held at the same angles with relation to the respective arms 22.

As a result, the jaws 32 tend to be held in proper position with relation to the post 16, which is being pulled or is about to be pulled.

In the practical use of my improved pulling device for pulling posts, such as the post 16, the standard 10 is placed on the ground adjacent to the post, as illustrated for instance in Figures 1, 2 and 4. The parts will then be in position, such that the vertical flange 16^a of the post will project into the groove 28 and thus stand between the jaws 32.

Assuming that the plate 26 is at the lower position of its movement and that the jaws have been spread sufficiently to receive the flange 16^a of the post, then when the lever 20 is operated to pull the plate 26 upwardly, the jaws 32 will engage and tightly grip the flange 16^a of the post.

The parts are so arranged that the members 30 having at their inner ends the jaws 32 are inclined upwardly and toward each other from their outer pivot pins 30^a, by

which they are pivoted to the lower ends of the arms 22.

The weight of the plate 26 tends to move the jaws to engaging position.

The spring A serves a double function. Primarily it tends to yieldingly press the plate 26 toward the post, so that it holds the plate against the post during the reciprocating movement of the plate when the lever is operated. This is a matter of great importance, because the spring A thus serves to hold the plate against the post at all times, so that the article engaging means can not swing away from the post during its reciprocation from gripping position to a new gripping position.

The spring also serves the purpose of causing a binding slightly on the plate and of causing the plate to bind slightly on the post. Thus there is created enough resistance to the movement of the arms 22 in response to the action of the lever 20 to insure the movement of the jaws to gripping position.

It is thus clear that with a device of this kind the article engaging means can operate on a post spaced laterally from the pulling device and the jaws can be caused to engage the post, pull it upwardly a short distance, and can then be slid down the post, during which movement they automatically disengage the post, and the pulling operation can be repeated, and this cycle of operations can be carried on until the post is pulled out of the ground.

While I have illustrated my device in the form in which it is constructed for pulling posts, it will be seen that it could be used for pulling other articles lengthwise or vertically or horizontally or otherwise, and by changing the parts slightly could be employed for a great variety of purposes.

I claim as my invention:

1. In a pulling machine, a standard, a lever fulcrumed on the standard, a plate, members pivotally mounted on said plate having gripping jaws, arms pivotally connected to said lever and to said members adapted to transmit movement of said lever to said members, and guide means supported on the standard serving to yieldingly engage said plate to hold it against the article to be pulled during reciprocation of the lever.

2. In a puller, a standard, a lever pivoted thereon, arms pivoted to said lever, article engaging means carried by said arms, comprising a plate, a pair of members pivoted on the plate having adjacent jaws, and having parts pivoted to said arms, whereby the means may be reciprocated by action of the lever for successively gripping an article at different points in its length and pulling the article lengthwise, and means carried by the standard for yieldingly holding the means against such article.

3. In a puller, a standard, a lever pivoted

thereon, a plate, members pivotally mounted on said plate having gripping jaws, arms pivoted to said lever and to the respective members for transmitting movement of the lever to the members, and a spring mounted on the standard, said plate having a sliding connection with the spring.

4. In a puller, a standard, a lever pivoted thereon, a plate, members pivotally mounted on said plate having gripping jaws, arms pivoted to said lever and to the respective members for transmitting movement of the levers to the members, and a spring mounted on the standard, said plate having a sliding connection with the spring, whereby the plate is guided and is yieldingly pressed against the article to be pulled.

5. In a post puller, a standard, a lever pivoted thereon, arms pivoted on the lever, a plate, jaws pivoted on the plate and pivoted to the arms, whereby the arms may be moved for moving the jaws to position for gripping an article spaced laterally from the standard, and the lever may then be further manipulated for pulling the article, and for then sliding the jaws along the article to a new gripping position, and yielding means tending to hold the plate adjacent to such article.

6. In a post puller, a standard, a lever pivoted thereon, arms pivoted to the lever to swing toward and from the standard, a plate, members pivoted to the plate, having adjacent ends formed with jaws and outwardly projecting ends pivoted to the respective arms, whereby the arms may be moved for moving the jaws to position for gripping an article spaced laterally from the standard and extending longitudinally substantially parallel therewith and the lever may then be further manipulated for pulling the article longitudinally of its axis and for then sliding the jaws along the article to a new gripping position, and means tending to cause the plate to frictionally engage the article and thus to resist the movement of the plate along the article in pulling direction for thus tending to move the jaws on their pivots to gripping position.

7. In a pulling machine, a standard, a lever fulcrumed on said standard, a plate, members 30, each having a gripping jaw formed on one of the ends thereof, means for pivotally mounting said members on said plate, arms pivotally connected to said lever and the other ends of said members adapted to transmit movement of said lever to said members, and resilient means carried by said standard and bearing against said plate, whereby to hold said members in operative position.

Des Moines, Iowa, April 18, 1928.
JOHN D. OTTO.
